GOLF PUTTER HEAD

Michael A. Dziurgot, 34242 Azter,
Westland, Mich. 48185

Filed June 11, 1970, Ser. No. 22,919

Term of patent 14 years

Int. Cl. D21—02

U.S. Cl. D34—5

FIG. 1

FIG. 1 is a front elevation view of a golf putter head embodying my new design.

FIG. 2 is a top plan view thereof taken on the plane 2—2 in FIG. 1.

FIG. 3 is a side elevation view of the golf putter head taken on plane 3—3 in FIG. 1.

FIG. 4 is a section view of the golf putter head, taken on plane 4—4 in FIG. 2.

I claim:

The ornamental design for a golf putter head, as shown.
